UNITED STATES PATENT OFFICE

ROBERT J. LOOCK, OF BALTIMORE, MARYLAND

CUSHIONING DEVICE

Application filed April 30, 1930. Serial No. 448,655.

This invention relates to a cushioning device for building closures, and more particularly to such devices in which utilization is made of the resiliency of the material, as well as the compression of air, to obtain the cushioning effect.

The object of the invention is to produce a simply made, inexpensive cushioning device which has a wide range of application, and one which can be attached to present structures without modifications. Other objects and advantages of the invention will herein-after appear in the following description, and the novel features thereof will be particularly pointed out in the appended claims.

In the drawing like reference numerals indicate like parts throughout the several figures, in which

Fig. 1 is a perspective showing the cushioning device applied to the door of an automobile, and specifically as lying between the hinge members of such a door, the attachment being made by a screw used to hold the hinge in place.

Fig. 2 is a plan view of the detached cushioning device.

Fig. 3 is a section through the device, and

Fig. 4 is a section through the device as it appears under compression,

Fig. 5 is a view similar to Fig. 3 showing a slightly modified form in which the extension 19 is omitted, and utilization made of an aperture in the base to insert a screw, and

Fig. 6 is a sectional view of this modified form.

In Fig. 1 are shown a frame element 10 and a door element 11 of an automobile. It will be appreciated that these two elements are indicative only of any building structures or analogous elements between which a cushioning device, to prevent jarring or rattling, is found desirable. The hinge plate 13 is secured to the jam, while the hinge plate 14 is secured to the closure element by screws, one of which, 15, is removed and utilized for the purpose of attaching the cushioning device 16. This cushioning device 16 consists of a base 17, having the form of a circle 18, with an extension 19, in which extension an aper-

ture 20 is provided for the insertion of the attaching screw 15.

While the base has been described as substantially circular, it will be appreciated that this base may have any form. Surmounting the base is a dome shaped portion 21 which is hollowed as at 22, imperforate at the base, but provided with a restricted opening 23 at the top of the dome. This construction leaves the walls surrounding the hollow or recess of the dome of a minimum thickness at the point 24, and increasing in thickness as it approaches the base. The merits of this formation will be apparent hereinafter.

Advantage is taken of both the cushioning qualities of the material of which the device is made, which is rubber of considerable stiffness, and also of the compression of the air entrapped in the hollow 22, when the closure is closed. As will be apparent from perusal of Fig. 4, where the door 11 is shown as closed against the jam 10, the air in the hollow of the cushion is confined therein as indicated, while the wall surrounding the apex of the dome is shown as flattened under the action of the closure. In arriving at this condition, it will be apparent that first the door will flex one side of the dome slightly and some of the entrapped air will be released

before the door closes completely the opening at the apex of the dome. After the door covers the apex of the dome, no more air will be permitted to escape, and from this point on, the device relies as well upon the compression of the air for its cushioning effect as upon the distortion of the walls of the dome. As pointed out, these walls become thicker as they approach the base, and consequently the cushioning effect, due to the thickening of the walls as well as the compression of the air, increases as the door reaches a closed condition.

It will be appreciated by reason of this action, that advantage is taken of both resiliency of the material as well as the compressibility of the air, to produce a satisfactory cushioning device, and this produces a cushioning of a wider range of application than one which would rely solely upon the resiliency of the material, or solely upon the

compression of the air, as it permits the escape of some of the air, especially when the width between the faces of the elements to be cushioned is narrow, as shown in Fig. 4, 5 while at the same time, if this space were wide less air would be permitted to escape and a satisfactory cushioning effect would be obtained for such wider space.

In Fig. 5 is shown a slightly modified form. 10 Here the extension 19 is omitted and the base made in the form of a true circle. An aperture 26 is formed in the base in alignment with the restricted opening in the apex of the dome through both of which openings the 15 screw 27 is inserted to attach the cushioning device to the wall. The dome 25 is otherwise similar to the dome in the preferred form.

This modified form is capable of a variety 20 of uses, particularly on house doors, screen doors, and on the legs of chairs, typewriters, adding machine, toilet seats, portable machines of different kinds, and for all purposes where a cushioning device under anything would eliminate noises or scraping, or 25 where a cushion is an advantage or desirable to be used between two movable parts.

It will be appreciated that in this modified 30 form the flexing of the dome protects and further restricts the opening in the apex thereof so that it will partly cover the head of the screw and thereby avoid any scratching that the head of the screw would cause to surfaces on which an articles carrying 35 this cushioning device would be placed.

35 What is claimed is:

1. In a cushioning device, a flat base of hard rubber or the like, a dome formed on said base, a recess formed in said dome and opening only at the apex thereof.

- 40 2. The cushioning device of claim 1, in which the walls of the dome are arcuate and increase in width as they approach the base.

- 45 3. In combination with a jam and a hinged closure, a cushioning device lying between said hinged elements in such a way that a lateral approach of the closure is produced, a cushioning device consisting of a dome shaped element, mounted upon one of the said closure elements, and made hollow with an opening at the apex thereof, to entrap air when the closure has swung sufficiently to cause a closing of the opening at the apex.

In testimony whereof I affix my signature.
ROBERT J. LOOCK.
